METHOD OF MAKING PAPER PRODUCTS

F. Warner Robinson, New York, N. Y.

Application May 27, 1935, Serial No. 23,583

3 Claims. (Cl. 92—40)

This invention relates to the manufacture of paper and articles made therefrom.

The object of this invention is to provide paper, cardboard, pulp and the like, having a manipulating element such as tape, cord, string, thread, wire, or bands of textile fabric, embedded therein in such a fashion that the manipulating element may be used to tear, rip or lift in a predetermined manner, the paper or other material 10 in which it is embedded, especially after such paper, or other material is made up into cartons, boxes, containers, stoppers, closures, caps, etc.

Cords or threads have been heretofore attached 15 to one side of the paper or pulp for the purpose of later using them to tear the paper. Threads or cords so attached are liable to become loosened in the handling of the paper, as when the paper is cut and folded in different serviceable forms. 20 Furthermore threads or strings adhering to one surface of the paper project beyond the surface and destroy its smooth surface. In certain kinds of containers or coverings for foodstuffs, either liquid or solid, it is undesirable and unsanitary to 25 have anything adhere to the paper, or project beyond its lateral surface, as string, immediately coming into contact with or accessible to the food, as would be the case if attached strings projected from the surface of the paper.

30 By my method these difficulties are overcome for I embed the manipulating elements in the paper itself so as to be substantially flush with one surface thereof and consequently these elements can not come off in a later handling or cutting of the paper. The invention furthermore lends itself to fully embedding the manipulating elements so as not to have the objection of projecting from the surface of said paper.

By the term paper I mean paper in its broadest 40 sense, and particularly such paper as may be used for containers, cartons, stoppers, closures and the like.

The most advantageous time to embed this manipulating element in the paper is during its 45 manufacture while the pulp sheet is still soft and pliable. Instead of burying my manipulating elements in the body of the paper, or enclosing them in the mass of pulp or attempting to interlock, enmesh or interweave the pulp fibre with them as 50 in the case where reinforcing strength is sought, my object is to embed my manipulating elements in one side of the paper only and to do it in such a way that they will be firmly cemented within the sheet at the surface. By doing this, the manipulating elements will so far as possible

retain their original shapes and integrity and will remain entirely free from interlacing and enmeshing pulp fibers. I accomplish this by separating and depressing the pulp fibers of the damp sheet of pulp or paper in the process of making the same with an instrument adapted to pry apart and to create a clean trough or track along the paper longitudinally so that when the manipulating element is fed to the moving sheet it will be guided into the track or groove so that the submerged portion of the element will retain, so far as possible, its original cross-sectional shape after the sheet is passed through the successive pressure rollers, drying rolls, calendering rolls, etc. found in the ordinary Fourdrinier machines or other types of machines usually required to produce paper. 10

Figure 1 is a perspective view of part of a paper making machine showing one method of 20 making proper grooves on the damp paper or pulp and then applying the manipulating elements in the grooves.

Fig. 2 is an enlarged sectional view of two types of the grooving rollers.

Fig. 3 is a sectional view of the finished paper 25 showing two forms of the manipulating elements in the paper.

Fig. 4 is a plan view of a die cut blank, 30 scored at the proper places, from which a container can be folded.

Fig. 5 is a perspective view, partially cut away, of a finished container showing the tearing element ready to be pulled to open said container.

Fig. 6 is an enlarged view of a portion of the 35 container shown in Fig. 5, showing the tearing element started.

Fig. 7 is a plan of a strip of paper with lifting element and from which bottle closures are to be cut.

Fig. 8 is a section on line 8—8 of Fig. 7. 40

Fig. 9 is a top view of a bottle closure inserted in a bottle.

Fig. 10 is a sectional view on line 10—10 of Fig. 9.

Fig. 11 is a perspective view illustrating the 45 manner in which the tab end of the lifting element may be used to raise the closure.

Fig. 12 is a section view of a paper container with closure and lifting element.

By reference to Fig. 1, a damp or pliable paper 50 or sheet of unfinished paper or pulp 1 is seen moving into the rollers 10 and 11. Before reaching these rollers, the sheet passes over roller 9 and at point of contact with this roller the upper surface of the paper is engaged by rollers 3, 4 and

5 which sink tracks or grooves of a design pre-determined by the contours of the peripheral edges of such rollers. Depression rollers 3, 4 and 5 (or any additional rollers of this type) are 10 mounted on a shaft 2 extending at right angles across the sheet, the shaft 2 being set in suitable bearings and arranged so that it may be easily raised or lowered to regulate the depth of the depression grooves 6, 7 and 8. The depression rollers 3, 4 and 5 may be spaced any desired distance apart and held in place on the shaft by some such settable means as set-screws 22; or they may be set in gangs of one or more types of edges, alternated or grouped as desired, 15 and any number desired may be operated at one time. The grooves or tracks may be placed at any desired position on the paper, keeping in mind the size of the paper and the size and conformation of the container or closure to be cut 20 therefrom so that the manipulating elements will come at the desired place in the finished article.

The manipulating elements 19, 20 and 21 are fed into grooves 6, 7 and 8 through guides 16, 17 and 18 mounted on guide-bar 15, the guides being adjustable, as for instance, by set screws 31, to line up with the depression rollers. The manipulating elements are drawn from their carrier reels and preferably through an adhesive bath or over a sizing roller before passing through the guides and to the depression grooves. As the paper moves forwardly the manipulating elements are drawn with the paper between pressing rollers 10 and 11, which press them firmly into the grooves. In passing through the adhesive bath or over the sizing rollers the threads will pick up sufficient adhesive material to aid them in staying firmly in the grooves. After passing rollers 10 and 11, the paper sheet loaded with 40 the manipulating elements may be finished in the same way as any other kind of paper or cardboard. It may be sized or filled or calendered as desired. Preferably the outer side of the manipulating element is made flush with the surface of the paper. If it is desired the said element may be left in substantially its original form in cross section or it may be flattened on its outer side while remaining substantially in its original form on its inner side as at 19 in 50 Fig. 3. This is governed by the pressure on the loaded paper and the depth of the grooves in relation to the cross sectional dimensions of the manipulating elements.

The manipulating element is firmly embedded 55 in its place by pressure during the process of producing the finished sheet and it may be further secured by adhesive, but its fibres are not interwoven or enmeshed with the paper fibre.

There may be many types of depression rollers 60 to meet the requirements imposed by different kinds of manipulating elements. Fig. 2 shows two types of such rollers having different peripheral edges. Edge 23 is used where a round manipulating or ripper thread is required in the finished sheet; and edge 24 is employed where a flat tape or textile fabric is required for lifting purposes or for ripping out a predetermined section from the carton or other type of container or closure made from the finished sheet of cardboard or paper.

Fig. 3 shows two types of manipulating elements embedded in the finished sheet, the drawing being an enlarged cross-section of a piece of finished paper or cardboard. The manipulating element 19 may be a thread or wire for use

where such an element may be preferable for tearing, while the manipulating element 21 may be a band or tape of textile material useful for lifting. These are used for tearing or lifting predesigned sections or closures from various devices. Both of these types of elements may be embedded in a sheet of paper or cardboard at one time or either type may be run in multiple places, as desired. The embedded thread or cord 19 shown in Fig. 3 may be obtained by making 10 a shallow groove in relation to the thickness of the thread 19 and the amount of pressure to be applied later in finishing the paper. It is noted that the inner or tearing side of the manipulating thread 19 remains substantially the same in cross section as before pressing. If the element 19 is desired substantially circular in cross section groove 6 may be deepened or the pressure of rollers 10 and 11 lessened or both of these things may be done.

Fig. 4 shows a die struck blank of a cardboard carton struck from a roll of cardboard in which has been embedded the cutting thread 10. The broken lines 27 show the scoring die struck for folding. Heavier lines 28 show where cutting 25 die has severed the cardboard. When this blank is folded as in Fig. 5 the manipulating element, in this instance a ripping cord 19, will be found on the inside surface of the carton encircling the top section thereof. A tab such as 25 may be 30 cut in one side of the carton blank if desired. Also, if desired, the cord 19 may be cut as at 26 or in other desired places, so that the opening may be of any size desired. By pulling the tab 25 which appears on the outside surface of the 35 finished carton (by virtue of the tab cut out at the point where there is an overlapping pasted seam) the manipulating or ripping cord, being a part of the tab, will cut or tear the container along its grooved bed all the way around the container. Or if desired the tearing cord 19 may be 40 stopped at 26 where the cord has previously been cut by the shaping die at the time the carton was originally die struck. The cut 26, of course, may be so arranged that it may come at any place 45 on the manipulating thread in the finished carton and so make whatever opening may be desired.

Figs. 7, 8, 9, 10 and 11 show how a manipulating element can be applied for lifting milk bottle 50 stoppers. The manipulating element 21, in this instance a lifting element, has already been embedded in the sheet of paper 1 in the manner described and the paper die cut in the form of milk bottle stopper 29 with lifting tab 25. It is 55 noted that the lifting tab 25 contains embedded in it the manipulating element 21. After the milk bottle stoppers have been cut out of the piece of paper they may be placed in the top of the milk bottle with the tab 25 sticking up so that it may be easily seized by the fingers. By grasping tab 25 and pulling it, it is obvious that the manipulating element 21 being embedded in the bottom side of the closure and being firmly attached thereto by embracing pressure of the 60 groove and an adhesive, will greatly facilitate the lifting of the closure and will permit the closure to be removed without tearing away the tab or pealing the cardboard off in layers as is frequently the case (when the closure is damp) 65 70 in other types of similarly shaped closures made entirely from cardboard or pulp. In the case of my closure, the point of greatest pressure during the pulling is at the bottom or lower side of the closure where the lifting element is a tape or 75

textile fabric much stronger than the layer-bond of cardboard. Thus my invention makes a more reliable and durable closure than cardboard alone and the closure can be used over and over again as long as is necessary. This makes it useable again by the user if the whole contents of the bottle are not wanted at one time.

Fig. 12 discloses another method of using stoppers with lifting or manipulating elements embedded therein as previously described. A paper container 30 is shown with the cap or closure 29. The lifting element 21 runs across the bottom surface of the stopper and ends in the tab 25.

The kind of manipulating element employed in any case will, of course, depend upon a number of factors: the weight, or thickness, or toughness, of the body material, the purpose for which it is to be used, the amount of resistance to be overcome (either with tearing or lifting), the size, shape, or design, of the opening desired, etc. In some types of containers it may be desirable to use more than one kind of manipulating element, or to use different kinds in combination to produce a predetermined result; such, for instance, as a hinged lip, made by tearing a section of the container and lifting the torn portion of it to a desired position, or removing it entirely.

It is understood, of course, that to accomplish the results explained here, the manipulating element must be placed in that side of the cardboard or paper which is the inside of the container when the latter is charged and ready for opening; and in the case of the stopper, cover or closure, the said manipulating element is placed in that side of the closure which is the lower or bottom side of such closure when the same is correctly seated.

What I claim is:

1. In the method of securing a tearing element to paper, the steps comprising sinking a groove in unfinished paper during the process of producing the finished sheet, said groove forming a bed for the laying in of said tearing element so that the embedded face thereof will remain substantially round in cross-section throughout the finishing operations of the paper, said groove being of such depth that the outer face of said tearing element is substantially flush with the surface of said paper, thereafter laying the tearing element in the groove and finishing the paper. 5

2. In the method of securing a tearing element to paper, the steps comprising sinking a groove in unfinished paper during the process of producing the finished sheet, said groove forming a bed for the laying in of said tearing element so that the embedded face thereof will remain substantially round in cross-section throughout the finishing operations of the paper, thereafter laying the tearing element in the groove in such a manner that the tearing element is retained within said preformed groove without intermingling of fibres between said element and the paper and finishing the paper. 10 20 25

3. In the method of securing a tearing element to paper, the steps comprising forming a groove in the paper, said groove forming a bed for the laying in of said tearing element so that the embedded face thereof will remain substantially round in cross section thereafter, said groove being of such a depth that the outer face of said tearing element is substantially flush with the surface of said paper, and thereafter laying and 30 35 pressing the tearing element in the groove while maintaining its paper-contacting face substantially round in cross section.

F. WARNER ROBINSON.
